FLUORESCENT LIGHT FIXTURE

Filed March 31, 1944

FIG. 1.

FIG. 2.

FIG. 3.

inventor:
Eugene Hughes Bradley

UNITED STATES PATENT OFFICE

138,370

DESIGN FOR A FLUORESCENT LIGHT FIXTURE

Eugene Hughes Bradley, Chicago, Ill.

Application March 31, 1944, Serial No. 113,093

Term of patent 7 years

(Cl. D48—23)

To all whom it may concern:

Be it known that I, Eugene Hughes Bradley, a citizen of the United States, residing at 227 North Central Avenue, in the county of Cook and State of Illinois, have invented a new, original, and ornamental Design for Fluorescent Light Fixture, of which the following is a specification, reference being had to the accompanying drawing, forming part thereof.

Fig. 1 is a side elevational view of fluorescent light fixture showing my new design;

Fig. 2 is a top plan view; and,

Fig. 3 is an end view thereof.

I claim:

The ornamental design for a fluorescent light fixture, as shown.

EUGENE HUGHES BRADLEY.
